UNITED STATES PATENT OFFICE.

THOMAS C. OAKMAN, OF AURORA, ILLINOIS.

DESIGN FOR A MEDAL.

SPECIFICATION forming part of Design No. 21,272, dated December 29, 1891.

Application filed August 8, 1891. Serial No. 402,178. Term of patent 3½ years.

To all whom it may concern.

Be it known that I, THOMAS C. OAKMAN, a citizen of the United States, residing in Aurora, in the county of Kane and State of Illinois, have invented a new and original Design for a Medal, of which the following is a specification, reference being had to the accompanying drawings, forming part thereof.

Figures 1 and 2 are drawings of the obverse and reverse sides of the medal.

The leading feature of my design is a medal in form of a Maltese cross having a round or oval medallion in the center and bearing in relief on the obverse side in the central medallion a portrait of Columbus,

with a scene from the life of Columbus on each of the arms of the cross, and on the reverse side in the central medallion a representation in relief of a statue of Columbus, with representations of buildings to be erected 20 for the Columbus centennial, to be held in Chicago, on the arms of the cross.

What I claim is—

The design for a medal, as herein shown and described.

THOMAS C. OAKMAN.
